UNITED STATES PATENT OFFICE.

BENJAMIN W. PUTNAM, OF JAMAICA PLAIN, MASSACHUSETTS.

APPARATUS FOR TREATING TEXTILES AND OTHER MATERIALS.

1,387,072.

Specification of Letters Patent.

Patented Aug. 9, 1921.

Application filed June 3, 1918. Serial No. 238,038.

To all whom it may concern:

Be it known that I, BENJAMIN W. PUTNAM, a citizen of the United States, and resident of Jamaica Plain, county of Suffolk,

5 State of Massachusetts, have invented an Improvement in Apparatus for Treating Textiles and other Materials, of which the following description, in connection with the accompanying drawing, is a specification, 10 like characters on the drawing representing like parts.

This invention relates to improvements in apparatus for treating textile and other materials which are to be acted upon by one or 15 more agents in the course of their treatment.

The principal object of the invention is to maintain the fibers or other elements of the material being treated in substantially their original relation to each other throughout 20 the treatment or series of treatments to which the material is subjected.

The invention therefore comprehends broadly mechanisms for treating materials either in dry state or by the action of liquids 25 or gaseous fluids or other agencies such as heat, light or electricity without material disturbance of the arrangement of the fibers or elements thereof.

More specifically the invention relates to 30 improvements in cleaning and scouring apparatus in which the material while confined in a thin layer is subjected to mechanical or chemical agencies, duly washed and dried without substantial disturbance of the relations 35 of the elements of the material.

The invention also comprehends the production of mechanisms for performing other treatments of material such as mercerizing, 40 carbonizing, bleaching, all of which may be introduced as steps in the process of transforming in a continuous operation raw fibers or other material into a product adapted to be utilized directly in the manufacturing arts.

Preferred embodiments of the invention 45 are disclosed herein as particularly applied to the treatment of wool in the fleece but it will be understood that the disclosure is of an illustrative character merely and not restrictive and that the apparatus may be employed 50 in the treatment of other materials of various characters, for example the apparatus is particularly adapted to be used in whole or in part in cleaning fabrics and made up clothing, one of the important uses of the invention being in the cleaning of uniforms and

other garments, not only for the purpose of removing dirt, grease, etc., but also to destroy vermin, germs, etc., which may be carried thereby.

The apparatus is such that the cleaning operation may be performed in the field anywhere a small supply of water is available and with such rapidity as to permit the entire outfit of a company or regiment to be cleaned in so short a time that the wearers 65 will not be seriously inconvenienced.

Inasmuch as the treatment of wool to prepare the fiber as it comes from the sheep for use in the textile arts requires a process comprising a maximum number of steps the invention both as a process and the process and apparatus will be described as employed in the treatment of wool.

Wool as it comes from the sheep contains many substances beside the wool fiber itself 75 which must be removed before the latter can be dyed, carded, combed and spun. These substances are, first, matter mechanically adhering to the wool, such as dirt, pieces of leaves, etc., which are readily removed by a 80 process of scouring, burs which adhere with tenacity to the wool, which may be removed by carbonization, and several other substances secreted from the sheep which are largely salts derived from the soil and assimilated by the sheep through its food. Such secreted substances can be divided into two classes, the first of which is known as "yolk" 85 or "suint" which comprises exudations from the skin of the sheep and which substance is 90 soluble in water, and the second known as wool fat which is insoluble in water but can be removed by alkaline liquids.

In scouring wool by processes and apparatus heretofore employed the wool is generally first passed through a stream of running water and is agitated therein by rakes or pickers, this treatment serving to remove the dirt and "yolk" or "suint." The wool is then carried to a scouring solution, which 95 is a soap or other alkali and is spread around or tossed through such solution until the wool fat is extracted, whereupon the wool is carried to a washing tank where it is again washed with running water. The wool is 100 then taken out and dried and is afterward subjected to various operations such as carbonizing, mercerizing, bleaching, dyeing, etc., each of said operations being performed 105 separately.

During the treatment of the wool by the various processes and apparatus heretofore employed the fleece is broken up by the rakes or other mechanism which are used to agitate the wool during the washing and scouring steps and many of the fibers of the wool are broken thereby. Other fibers both short and long are caused to form knots or noils and cannot be combed, so consequently become waste.

10 This is particularly true of fleeces from hot countries in which the sheep are shorn twice a year, the wool of such fleeces being too short to withstand economically the usual 15 scouring and combing treatments.

By the present invention the fibers of the fleece are maintained throughout the treatment in a state of tension of such a character that the fleece remains substantially intact 20 with the fibers in their original relative positions so that when the fleece emerges from the treatment or series of treatments the fibers are in their original condition without broken fibers or noils so that when subjected 25 to combing and other treatments there is substantially no waste.

In the scouring treatment of wool it is important that the scouring liquor shall not be either too hot or too strong or both, as excessive heat or excessive strength causes deterioration of the fiber.

Another object of the present invention is to provide means whereby the strength of the solution may be at all times under control, a 35 minimum amount of solution used and the wool treated just such predetermined length of time as is necessary most effectively to perform the scouring operation.

A further feature of the invention consists 40 in providing means whereby the temperature of the liquid will always be under control whether the liquid be merely water or scouring, bleaching, or other chemical solution.

A further feature of the invention consists 45 in providing means for subjecting the material to the action of steam while it is in the process of treatment, the steam being produced from water first passing through the material.

50 A further object of the invention is to provide means for handling the fleece in which inspection of the fleece may be made at any time in order to determine whether the proper results are being obtained from the treatment during any step of the process.

Various other features of the invention will be apparent from the following description and drawings and will be pointed out in the annexed claims.

60 The preferred form of apparatus which is illustrated in the accompanying drawing and which while particularly adapted for the treatment of wool is also capable of use in the treatment of various other materials 65 comprises means for mechanically treating

the fleece or other material to beat out the dirt and refuse and thereafter while the fleece is maintained intact to scour the same, wash, bleach, carbonize, mercerize or dye the fleece with suitable washing steps intermediate these various treatments and finally to dry the fleece and deliver the same from the machine still in substantially intact condition.

70 In this apparatus one of the objects of the invention is to provide means for beating out the dirt and other solid matter without disturbing the arrangement of the fibers of the fleece.

75 Another object of the invention is to obtain a maximum amount of space and with a minimum amount of liquid. This is accomplished by passing the fleece which is spread out into a flat condition through the liquid in the direction of its length or edgewise, preferably causing the fleece to pass obliquely downwardly into the liquid and again obliquely upwardly whereby a maximum amount of travel through the liquid in a tank of a given size is obtained, the tank preferably being V-shaped with its bottom walls 80 conforming substantially to the directions of movement of the fleece.

85 Other important objects of the invention consist in alternately compressing and permitting the fleece to expand during its passage through the liquid, means also preferably being provided for agitating the fleece transversely in the liquid whereby the liquid will be forced through the interstices between the fibers and through contact of the liquid with each fiber insured.

90 A further object of the invention is to economize in the amount of liquid or chemicals used and this is effected in the preferred form of the invention illustrated herein by providing means for squeezing as much as possible of the liquid or chemical from the fleece as it passes from one liquid treating operation to another.

95 Another feature of the invention consists in providing heating means for each of the liquid containing tanks which will be always under control of the operator and in which a minimum amount of fuel will be required to 100 maintain the liquid at exactly the proper temperature or temperatures.

110 Another object of the invention is to provide means for thoroughly drying the fleece or other material treated in the manner aforesaid without disturbing the relation of the fibers of the wool or other elements of the material being treated.

115 This is accomplished by passing the fleece or other material through a drying oven, 120 preferably around drying drums adapted to maintain a constant circulation of heated air through the material being treated and finally delivering the material in a thoroughly dried state.

Another feature of the invention consists in providing means for utilizing the excess of the heat supplied in the drying operation to heat the liquid which is used in the wet treatment of the material.

The preferred form of apparatus utilized for accomplishing these results as illustrated herein comprises a plurality of traveling perforated endless conveyers or belts having adjacent leads moving in the same direction and preferably at the same speed. The adjacent leads of these endless conveyers are placed in close proximity to one another so that they are adapted to confine the material, such as a fleece of wool, between them in the form of a flat layer.

The material thus confined between the adjacent leads of the endless conveyer is first subjected to a beating operation in which a series of beaters are caused to impinge upon the upper lead either directly or preferably upon a stationary flexible material located over the conveyer and adapted to permit the action of the beaters therethrough so that the dirt or other solid debris will be driven from the wool or other material through the lower coöperating conveyer lead.

The parallel leads of the endless conveyer are thence guided through tanks containing the various liquids or chemical solutions adapted to perform the functions above described and finally through a dryer, the fleece or other material at all times being confined between the same portions of said conveyers and finally discharged substantially intact.

Where wool is being treated the coöperating leads of the conveyers seize the wool as it is presented to the bite of the rollers around which the endless conveyers pass and impose a tension upon the fibers which tends to straighten them. This tension is preserved to a greater or less extent during the entire treatment so that when the wool emerges from the final treatment many of the curled up noils or knots are straightened out so that tags, waste and wool of such character which heretofore has been considered waste is transformed into a suitable material which can be used with the ordinary wool stock.

It will be understood that in this apparatus various novel details have been invented and developed as subcombinations of my invention, said novel details being more fully pointed out in the following description and claims.

The drawings illustrate portions of apparatus embodying my invention and a preferred means for performing the various steps of the process which also forms my invention.

In the drawings:

Figure 1 is a side view of a cleaning and scouring apparatus embodying my inven-

tion, portions of said apparatus being broken away because of lack of space to illustrate the entire apparatus.

Fig. 2 is a similar view of the opposite side of the apparatus illustrating the mechanism for driving the conveyers.

Fig. 3 is a side view of the modified form of apparatus in which the drying mechanism is located beneath the liquid tanks.

Fig. 4 is a vertical sectional view through the dryer on line 4—4 Fig. 1.

Fig. 5 is a transverse sectional view through one of the drums.

Fig. 6 is a plan view of a section of the dry cleaning apparatus showing the perforated endless carriers, a flexible stationary member, such as a canvas plate overlying the same and beaters acting upon the surface of the stationary flexible member.

Fig. 7 is a longitudinal sectional view of a modified form of beating apparatus.

Fig. 8 is a vertical longitudinal sectional view through one of the liquid containing tanks illustrating a preferred means for transversely vibrating the coöperating material confining leads of the conveyer during its passage through the fluid in the tank.

Fig. 9 is a detail side elevation of one of the last tanks showing a spray of water being projected upon the material engaging conveyers and means for supplying heat to the bottom of the tank to convert into steam spray which passes through the material.

Fig. 10 is a view of the preferred form of conveyer supporting and squeezing rollers showing the conveyers in section.

Fig. 11 is a detail sectional view showing the means for splicing the ends of the webs of the endless conveyers.

The machine illustrated in the accompanying drawing comprises a series of vertical posts 1, which support side frames 2, 3 upon which are supported means for carrying superposed conveyers preferably endless webs of reticulated wire fabric having adjacent leads traveling in the same direction and lying sufficiently close to each other to confine the material lying sufficiently close to each other to confine the material between them to prevent the elements thereof from any considerable movement relative to one another.

As illustrated in Figs. 1 and 2, three of such endless conveyers are provided; the lower conveyer 4, which receives the material to be treated, has an upper horizontal lead supported upon rollers 5 through a compartment in which the material is treated mechanically, preferably by beaters, or by an air blast forced downwardly through the material.

The conveyer 4 after emerging from the beating compartment passes between a pair of guide rollers 6, 7 and is led over the latter downwardly beneath a roller 8 at the

bottom of a tank preferably having flat downwardly converging bottom plates 9, 10 forming a V-shaped tank, the roller 8 being located in the lowermost portion of the tank.

5 After passing beneath the roller 8 the conveyer is carried over a roller 11 mounted upon the edge of the tank preferably above the surface of the liquid in the tank. A coöperating squeezing roller 12 may be 10 utilized to force the liquid out of the material as it is passed over the roller 11. The roller 11 desirably may be crowned and the coöperating roller provided with a concaved surface corresponding in curvature to the 15 crowned roller 11. By this construction tendency of the conveyers running over the same to creep laterally is counteracted.

Any suitable number of other tanks similar to the one described may be provided 20 and said tanks may be filled with water or any desired chemical solution for operating upon the material. These tanks may be located in a continuous row if sufficient room is available but if it is desired to economize 25 in floor space another series or a number of series of tanks may be superposed.

As shown in Fig. 1 of the drawings the second series of tanks is superposed above the first and the conveyer 4 is led upwardly 30 to discharge the material resting thereupon upon a suitable conveyer for carrying the same through the upper series of tanks which as shown herein are retained between the side frames 3.

35 The conveyer 4 is then carried around any suitable guiding rollers beneath the tanks along the bottom of the frame of the machine and finally passes over the roll 5 herefore described.

40 Any suitable arrangement of conveyers for effecting the purpose may be utilized. As illustrated herein however, the upper of the superimposed conveyers which engage the material in the lower series of tanks is 45 used for the lower conveyer of the upper series of tanks. This conveyer 13 is first carried beneath guide rollers 14 extending across the beating compartment, thence beneath the roller 6 and over the conveyer 7, 50 thence downwardly beneath the rollers 8 and upwardly over the rollers of the successive tanks 11 in parallelism and in co-operation with the conveyer 4. The squeezing rollers 12 which may be located at any 55 desired points along the tanks engage the conveyer 13 and force the same upon the material so that the liquid is squeezed from the material lying between the two leads as they pass together between the rollers 60 11—12. Where superposed series of tanks are used such as illustrated in Figs. 1 and 2 the conveyer 13 leads upwardly at the end of the frame in conjunction with the conveyer 4 and then becomes the lower lead 65 of the coöperating leads which carry the

material through the upper series of tanks. These tanks may, like the tanks heretofore described, comprise converging bottoms 15, 16 having guiding rollers 17 corresponding to the rollers 11 located at the upper edges 70 of the tanks and guiding rollers 18 corresponding to the rollers 8 located near the bottoms of the tanks. The squeezing rollers 19 coöperating with any suitable number of rollers 17 may be provided as before described.

The conveyer 13 may thus be led through any number of tanks containing various liquids or chemicals adapted to perform the desired operations upon the material and 80 delivered therefrom either directly or carried through a dryer for removing such moisture from the material as is not squeezed out by the last of the squeezing rollers 19. In order properly to carry the 85 material through the upper series of tanks as aforesaid another perforated endless conveyer 20 is utilized which passes around a guiding roller 21 into coöperating relation 90 to the conveyer 13.

The conveyer 20 thereupon passes over the guide rollers 17 and beneath the guide rollers 18 in conjunction with the conveyer 13. The guide roller 21 desirably is located in such proximity to the guide roller 22 over 95 which the endless carrier 4 is guided that the endless conveyer 20 passing over the roller 21 will act as a doffer to remove from the conveyer 4 any material which may adhere to it and deposit the same upon the conveyer 13 so that it will be carried through the upper series of tanks in the manner aforesaid.

After passing through the series of tanks the leads of the conveyers 13 and 20 preferably pass into a drying chamber 23 through which the coöperating leads of said conveyers are carried preferably alternately below and above drums 24, 25 so that these 100 leads of the conveyers with the material 105 between them preferably travel in a sinuous course through the drying chamber.

The drums 24 and 25 preferably comprise heads 26, 27 (see Fig. 4) journaled upon hollow bearings 28 of the upper side frame 3, with gas pipes 29 extending through the bearings. The pipes may be provided with any number of holes to provide jets for heating the interior. The periphery 30 of the drum desirably is provided with longitudinal slots 31, the walls 32 of the slots being turned inwardly. By this construction the inturned walls 32 of the slots 31 form in effect fans which tend to draw air 115 into the drum during its rotation or to expel air therefrom, according to the direction in which the drum is rotated, thus the rotating drums which are heated from the inside not only act upon the material passing over them 120 to heat the material but also to force air 125 130 into the slots 31.

currents through the material, which will facilitate the drying operation.

Any suitable number of said drums may be employed and they may be arranged to 5 draw in and expel the atmosphere as may be desired. The upper portion of the drier may be provided with a hood 33 and with a chimney 34 as illustrated in Fig. 2 or the heating chamber may be located beneath the series 10 of tanks in the manner illustrated in Fig. 3 which will hereinafter be described.

Means preferably are provided for restricting the area of the opening in the bottom of the chamber to confine the air therein 15 and prevent the wastage of heat. Any desirable construction may be employed. A convenient means illustrated herein comprises a series of bottom plates 35, 36 secured to the side frames, and adjustable 20 plates 37, 38 connected to them by slot and screw connections 39, 40. By adjusting the edges of the plates 37, 38 more or less closely to each other the amount of air entering the chamber may be regulated. Of course any 25 other suitable regulating means may be employed.

After emerging from the drying chamber the endless carrier 13 passes around guiding rollers 41, 42 and thence downwardly beneath the rollers 14 as aforesaid. The lower 30 lead of the upper conveyer 20 after passing through the drier is guided beneath rollers 43 thence preferably beneath a roller 44 located beyond the roller 41 and thence over 35 suitable guides to the roller 21 at the opposite end of the machine. By suitable arrangement of the guiding rollers for the conveyers a space 45 may be provided for the feeding in of the material upon the upper lead of the conveyer 4 so that the material, such for example as a fleece of wool, 40 may be spread out flat thereupon and as the adjacent leads of the conveyers 4 and 13 advance preferably at the same speed the fleece 45 or other material will be clamped between them in the form of a thin layer. This layer 50 will be maintained in its original position between the leads of the conveyers 4, 13 and 20 during the entire treatment no matter to 55 how many different operations the same is submitted and will finally be discharged by the conveyer 13 as the latter passes over the roll 41 into a suitable receptacle such as a bag 46 or upon some other conveyer for transporting the finished material to other machines.

Any suitable means may be provided for driving the conveyers above described. A convenient mechanism which is illustrated 60 herein comprises a main driving shaft 47 which may be mounted in the frame, said shaft being driven by a suitable power mechanism through a belt 48 and pulley 49 mounted upon one end of said shaft (see 65 Fig. 1). The opposite end of the shaft 47 is

provided with a beveled gear 50 which meshes with a complementary beveled gear 51 upon a countershaft 52 from which other countershafts may be driven in any suitable manner to rotate any desired number 70 of rollers 11 and 17 and the squeezing rollers 12.

As illustrated herein the shaft 52 is provided with a sprocket wheel 53 which drives a sprocket chain 54 and thereby actuates a 75 sprocket wheel 55 which is fast upon a countershaft 56 running lengthwise of the upper frame 3. The shaft 56 has upon it worms 57 which engage worm gears 58 upon the shafts of certain of the rollers 17 thereby 80 rotating said rollers.

Suitable gears upon the shafts of the rollers 17 may be provided to engage gears 59 upon the squeezing rollers 19 and thereby 85 positively drive them. The second sprocket wheel 60 rigidly secured upon the shaft 56 actuates a sprocket chain 61 which in turn drives a sprocket wheel 62 upon a countershaft 64 mounted upon bearings alongside 90 the lower frame 2 and this countershaft is 95 likewise provided with worms 64 which actuate worm gears 65 to rotate the rollers 11. The shafts of these rollers 17 may be provided with gears 66 to actuate the squeeze rollers 12.

In the operation of the machine, the fibrous material or fleece of wool is presented to the converging leads of the upper and lower conveyers and as it is seized by said conveyers is drawn between them in such a manner as to impose a tension upon each fiber. This results from the fact that the elements of the reticulated conveyer engage the fibers upon both their upper and lower surfaces at several points as they draw upon the material while it is being fed between them and the tension thus created on each fiber is maintained during the progress of the material through the machine. Consequently, there is no opportunity for the 100 shorter fibers to contract and roll up into noils. The material therefore when discharged from the machine remains in the same condition so far as the relative arrangement of the fibers is concerned as when 110 it was introduced into the machine.

By this construction conveyers, 4, 13 and 20 may be driven at a uniform speed so that the adjacent leads of the conveyers which engage and confine the material between them will progress through the machine in unison at all times retaining the fibers under a proper tension and in substantially their initial arrangement and discharging the material in its original condition except for the 125 cleansing and other treatments to which it has been subjected.

It will of course be understood that any desired number of tanks may be utilized and that any desirable form of tanks may be 130

employed, said tanks desirably being either porcelain lined or provided with removable porcelain receptacles for the liquid which is used.

5 It will also be understood that the same solutions may be used in a single or in two or more adjacent tanks and that the squeezing rolls may be used to expel the water from the material as it emerges from each tank, 10 or that the squeezing rolls may be applied only where the conveyers pass from one solution to the next.

Any suitable means may be provided for supplying water to the tanks, a convenient 15 means comprising a pipe 67 leading from a suitable supply, said pipe 67 leading upwardly along one of the posts 1 and communicating with branch pipes 68, 69 which run along the side frames 2 and 3 respectively. The branch pipes 68 and 69 are provided with faucets 70 adapted to discharge into the respective tanks so that any tank may be replenished at will. If desired a pre-heating means may be provided 20 in order that water at any desired temperature may be supplied to the tanks.

If desired other water pipes for introducing cold water into the tanks may also be employed. In order to draw off the contents of the tanks discharge pipes 71 having valves 72 therein communicate with the bottom of each tank. The discharge pipes 71 of the upper and lower series of tanks preferably communicate with discharge pipes 35 73 and 74 respectively, the discharge pipe 73 desirably being provided with three-way valves 75 located over tanks in the lower series. By this means the solution from any of the tanks of the upper series may be 40 discharged into any of the tanks of the lower series or may be carried to a waste pipe.

It will therefore be seen that if the same solution is used in both the upper and lower 45 series of tanks and the solution in the lower series becomes exhausted or deteriorated it may be drawn off in whole or in part from the lower tank and a solution from the upper tank transferred into said lower tank, 50 thus permitting the upper tank to be refilled with a fresh solution.

Likewise the rinsing water in an upper tank may be drawn off to replenish the first cleansing water of the lower series of tanks, 55 thus saving water, which is very essential when a machine is installed where a limited supply of water is available.

In order to maintain the liquid in the tanks at desired temperatures means are 60 preferably provided for heating the bottoms of each tank. A preferred means which is illustrated herein as applied to adjacent tanks having V-shaped bottoms comprises a series of burners 76 located between the inclined bottoms of adjacent tanks and in such

position relative thereto as to heat most effectively said tanks. These burners may be supplied either with gas or other combustible fluid through mains 77, each burner being provided with a valve by means of 70 which the supply of fuel may be controlled. By reason of this construction the temperature of the liquid in each tank may be controlled and the wool or other material being scoured or treated may be subjected to 75 washes and solutions of exactly the proper temperature to obtain the maximum efficiency of action upon the material.

This is exceedingly important, particularly in wool scouring as it is desirable that 80 the wool shall be subjected to a washing solution of a temperature of substantially 100° F., thereafter to a saponaceous scouring solution at a somewhat higher temperature and again preferably to a similar solution at a still higher temperature and afterward to washing solutions of gradually lower temperature and finally to bleaching, dyeing or other solutions, the effective action 85 of which is more or less dependent upon the 90 temperature of the solution.

After the final treatment of the material whether it is merely a scouring treatment or a scouring treatment combined with a bleaching, carbonizing, mercerizing or other or all 95 of such treatments it is essential that the material shall be thoroughly washed so that all free chemical agents shall be removed therefrom before the material enters the drier. This may of course be accomplished 100 by passing the material engaging leads of the conveyer through a sufficient number of washing tanks and agitating the same therein in the manner heretofore described. A further treatment which is desirable consists in projecting upon the material, jets or a spray of water at any desired pressure in 105 such a manner that it will pass through the material and wash away any free substance which remains, either soluble or solid. To 110 this end one or more of the branch pipes 69 may be provided with a depending T-shaped member 78 which communicates with one or more transverse pipes 79 provided with ori- fices positioned to discharge jets upon the 115 material engaging leads of the conveyers as they pass through the last tank or such number of tanks as may be provided with such equipment. The discharge valves 72 of such tanks will of course be left open in order to dispose of the water which passes through the material and also the matter carried by it. In such treatment however, the bottoms of the tanks preferably are heated by the burners 76 to a sufficiently 120 high degree to convert into steam a substantial amount of the water thus projected through the material.

This steam rising through the material completes the cleansing of the material so 130

that it is in proper condition to enter the drier. A squeeze roll or a plurality of squeeze rolls engage the material engaging conveyers after they pass through the steam treatment and squeeze as much of the liquid as possible from the material before it enters the drier heretofore described.

As before stated it is desirable that means be provided for expelling the dirt and other free solid matter from the wool or other material to be treated preliminary to the washing and scouring operations.

A preferred mechanism for accomplishing this purpose which is illustrated herein comprises a series of beaters which are adapted to act upon the material while it is confined between the adjacent material engaging leads of the conveyers.

The beaters illustrated in Figs. 1, 2, 3 and 20 6 of the accompanying drawings comprise bars or cylinders 80 rigidly secured to the side frames 2 and extending across the conveyers a short distance above the upper material engaging lead of said conveyers. 25 Spring plates 81 are rigidly secured to the bars 80 and are provided at their free ends with upturned portions 82 allowing lifting devices to enter beneath them.

These beaters are raised and flexed by 30 pins 83 projecting from a cylinder 84 which is mounted upon a shaft 85 journaled in suitable bearings in the frame 3. The shaft 86 is provided with a sprocket wheel 86 which is rotated by a chain 87 from a 35 sprocket wheel 88 on the main shaft 47. Any desired number of beaters may be utilized and the actuating shafts therefor connected by chain and sprocket or other usual type of gearing not shown.

40 In order to protect the endless conveyers from the action of the beaters a web of canvas 89 or other tough flexible material is stretched just above the lead of the conveyer 13 which is acted upon by the beater. 45 This canvas may be secured to rolls 90, 91 journaled in the frame 3, pawl and ratchet mechanism 92, 93 being provided upon one or both of said rolls for imposing proper tension or taking up the slack in the canvas 50 as the same stretches.

In the operation of the machine the rotation of the roller 83 raises the free ends of the spring plates 81 successively against the action of their springs and releases them so 55 that the plates fly down and strike successively heavy blows upon the canvas which overlies the material engaging leads of the conveyers. The conveyers, as above stated, which are apertured and preferably are 60 made of reticulated wire cloth permit the dirt and other free material to be driven through the lower lead of the conveyer into a suitable receptacle from which it may be removed through a door, chute or pneumatic 65 conveyer (not shown).

In Fig. 7 I have illustrated a modified form of beater which comprises a series of spring plates 95 anchored at one end in a rotatable roller 96 which is suitably journaled in the frame of the machine and is 70 rotated in any desirable manner.

A series of bars 97 located at successively decreasing distances from the axis of the roller 96 engages each beater 95 as the roller 96 is rotated, thereby flexing the same into 75 the form of an arc as illustrated in Fig. 7. As the end of the arc passes over the last bar it preferably is substantially vertically above the axis of the roller 96. The spring is then released and by its resilience whips 80 down upon the canvas layer 89 striking a powerful blow thereupon.

These spring plates 95 may be arranged spirally or in any desired manner as will be readily understood.

It has been heretofore mentioned that it is desirable to agitate the material carrying leads of the conveyer transversely as the same pass through various liquids or solutions in the tank. A preferred mechanism 90 for accomplishing this purpose is illustrated in Figs. 1 and 8 which comprises one, or preferably a pair of arms 98, carrying at their lower ends pairs of guiding rollers 99, 100 embracing respectively the upper and 95 lower leads of the conveyer and extending the full width across the same. The arms 98 converge and at their upper ends have an integral boss 101 forming a cam strap which embraces a cam 102 mounted upon a 100 shaft 103 which may be carried by suitable bearings upon the side walls of the tank frames or upon the tanks.

The shaft 103 may be driven in any obvious manner from the transmitting mechanism. It will therefore be obvious that upon rotation of the shaft 103 the arms 98 will be alternately raised and lowered causing the material engaging conveyers to reciprocate transversely and thereby force the liquid through the material which is confined between the conveyers in a manner somewhat analogous to that in which hand scrubbing is done in laundry work, thus most effectively causing such a circulation 115 of the liquid that it will reach each individual fiber.

By setting the cams which actuate the agitating device in successive tanks at different angular positions no unusual strain will 120 be imposed upon the conveyers. In order however to avoid any damaging strain upon the same and also to keep the conveyers in proper relation to each other a yieldable guiding roller is provided which is analogous to a belt tightener and which may be adjusted to secure the desired tension upon the conveyers.

A convenient form of tension device of this type is illustrated in Fig. 1 and com- 130

prises a roller 104 mounted in suitable bearings 105 carried by guides 106 upon a bracket 107 secured to the main frame. The guides 106 are connected at their ends 5 by a plate 108 through which screws 109 extend, said screws being provided with hand wheels 110. The opposite ends of the screws are provided with disks 111 which engage the upper ends of springs 112, the lower 10 ends of which are seated upon the slideable bearings 105 of the roller 104.

By rotating the hand wheels 110 to advance and retract the screws 109 any desired tension may be imposed upon the co-operating 15 material clamping leads of the conveyers.

One of the minor features of my invention comprises a novel means for uniting the ends of the webs of material which form the 20 endless conveyers. This means is illustrated in Fig. 11 in which the ends of the webs 113, 114 are superposed and a previously prepared metallic plate 115 wrapped about them so as to provide parallel upper 25 and lower fabric engaging portions 116, 117. These fabric engaging portions previously have been perforated by a punch which causes burs 118 to extend from the walls of the perforations. By making alternate perforations 30 119, 120 of different sizes the clamping means may be so arranged that the burs of one set of alternate perforations 119 enter the burs 120 of an alternate set of perforations when the clamping strip is in 35 place.

By folding the clamping strip over the edge of the belt therefore until the perforations 119 and 120 come into registry then hammering the superposed portions of the 40 plates together the burs 119, 120 will be caused to pass through the webs of the conveyers and interlock so as firmly to secure the ends of the web together.

Any suitable perforated, reticulated or 45 porous material may be used for the conveyer belts, preferably a reticulated wire conveyer formed of flexible wire is used, such as copper wire, or galvanized iron wire. I have also discovered that iron wire 50 cloth may be provided with a protective coat of Portland cement which prevents the action of chemicals ordinarily used in scouring and other treatments of wool and therefore will preserve the life of the conveyer.

55 In Fig. 2 a modified form of the invention is illustrated in which the material is carried by endless conveyers having adjacent parallel leads through beating mechanism of the character above described, thence through 60 a series of tanks adapted to scour and perform the other treatments above described upon the material, the conveyers finally carrying the material through a drier which is located beneath the tanks of the conveyer so

that the excess of heat from the drier is utilized for heating the liquid in the tanks.

As illustrated in this construction two conveyers are used, one of said conveyers 121 being carried through a beating mechanism 122 which may be of the type heretofore 70 described, thence through a series of tanks 123 and from said tanks 123 around suitable guide rollers 124 and downwardly around drying drums 125, 126 which are located beneath the tanks 123, the lower lead of said 75 conveyer finally passing over suitable guiding rollers 127, 128 and again entering the beating compartment.

An upper conveyer 129 has its lower lead 80 guided in parallelism with the upper lead of the conveyer above described and serves to clamp the material during its passage through the beater and through the tanks as heretofore explained.

These conveyers pass around suitable 85 guide rollers 130 the upper lead of said conveyer going above the tanks and beating compartment. A third conveyer 131 cooperates with the conveyer 121 after the same passes the roller 124, the upper lead of 90 the conveyer 131 receiving the material as it is released by the conveyers 121, and 129 and co-operating with the lower lead of the conveyer 121 to carry the material through the drier.

95 The conveyer 131 together with the lower lead of the conveyer 121 passes around the drying drums 125 and 126 throughout the dryer and thence passes around a roller 132 being guided by other suitable rollers 133 beneath the frame of the drier. The lower lead of the conveyer 121 continues along 100 beneath the beating compartment so that the material carried between the conveyers 121 and 131 is discharged upon an endless conveyer 134 running transversely across the 105 machine as illustrated in Fig. 2, or into any suitable receptacle.

110 It will be understood that the mechanism disclosed herein is merely of an illustrative character and that the process may be performed by other means than that disclosed herein and that various other modifications in the apparatus may be made within the meaning and scope of the claims hereof; for example, any number of superposed tanks may be employed or the tanks may be made in units which may be conveniently assembled and knocked down for transportation, the latter being particularly desirable where 115 the process and apparatus is to be used for the purpose of cleaning soldier's uniforms, etc.

120 It will also be understood that my invention comprehends the application of the process and the apparatus to the treatment of any kind of fibrous, textile or other material which it is desired to treat in a series 125

of operations without disturbing the relative arrangement of the fibers or elements thereof.

Having fully described my invention, 5 what I claim as new and desire to secure by Letters Patent, is:

1. An apparatus for treating material comprising a plurality of simultaneously-movable reticulated members adapted to 10 clamp the material therebetween in a thin layer, means for moving said members in unison in the direction of their length with the material between them, and means acting on said material during the movement 15 of said members.

2. An apparatus for treating material comprising a plurality of traveling, reticulated, endless conveyers having adjacent leads simultaneously moving in the same 20 direction adapted to engage and clamp the material between them and means acting on said material while retained between said conveyers.

3. An apparatus for treating material 25 comprising a plurality of superposed, traveling, endless, apertured conveyers having parallel adjacent leads simultaneously moving in the same direction at the same speed adapted to engage and confine the material 30 between them and means for subjecting the material to dry and wet cleansing treatments while retained between said conveyers.

4. An apparatus for treating material 35 comprising a plurality of superposed, traveling, endless, apertured conveyers having parallel adjacent leads simultaneously moving in the same direction at the same speed adapted to engage and confine the material 40 between them, means for subjecting the material to dry and wet cleansing treatments while retained between said conveyers, and means for drying the cleansed material while retained between said conveyers.

5. An apparatus for treating material 45 comprising a plurality of superposed, traveling, reticulated, endless conveyers having adjacent parallel leads moving simultaneously in the same direction adapted to 50 confine the material in a thin layer between them, and means including beaters acting upon the material through one of the material-engaging leads to expel dirt and other debris from the material through the other material-engaging lead of said conveyer.

6. An apparatus for treating material 55 comprising a plurality of superposed, traveling, apertured, endless conveyers having adjacent parallel leads moving simultaneously in the same direction adapted to 60 confine the material in a thin layer between them, and means including a plurality of sets of beaters acting upon the material through the upper material-engaging lead 65 to expel dirt and other debris from said

material through the other material-engaging lead.

7. An apparatus for treating material comprising a plurality of superposed, traveling, apertured, endless conveyers having 70 adjacent parallel leads moving simultaneously in the same direction adapted to confine the material in a thin layer between them, means including beaters acting upon the material through the material-engaging lead to expel dirt and other debris from said material through the other material-engaging lead, and flexible, stationary, protective means intermediate of said beaters and said upper material-engaging lead. 75

8. An apparatus for treating material comprising a plurality of parallel, reticulated, endless conveyers having parallel adjacent leads simultaneously traveling in the same direction and acting to clamp a thin 85 layer of the material between them, a tank of liquid and means for guiding the material-engaging leads of said conveyer through the liquid in said tank.

9. An apparatus for treating material 90 comprising a plurality of parallel, reticulated, endless conveyers having parallel adjacent leads simultaneously traveling in the same direction and acting to clamp a thin 95 layer of the material between them, a tank of liquid, means for guiding said conveyer through the liquid in said tank in directions obliquely downward and thereafter obliquely upward relative to the surface of the liquid and means for squeezing said material between said conveyers during its progress 100 through said liquid.

10. An apparatus for treating material comprising a plurality of parallel, apertured, endless conveyers having parallel adjacent leads simultaneously traveling in the same direction adapted to retain a thin layer of the material between them, a tank of liquid, means for guiding said conveyer through the liquid in said tank, and means for vibrating said conveyers during their 105 passage through said liquid whereby the liquid will be forced through said conveyers and the material confined therebetween. 110

11. An apparatus for treating material comprising a plurality of parallel, apertured, endless conveyers having parallel adjacent leads simultaneously traveling in the same direction adapted to retain a thin layer of the material between them, a tank of liquid, means for guiding said conveyer through the liquid in said tank, means for squeezing said material between the said conveyers during its progress through said liquid, and means for vibrating said conveyers during their passage through said liquid whereby the liquid will be forced through said conveyer and the material confined therebetween. 115 120 125

12. An apparatus for treating material 130

comprising a plurality of superposed, apertured endless conveyers having adjacent parallel leads traveling in the same direction adapted to confine a thin layer of the material between them, a V-shaped tank of liquid, and means for guiding said parallel leads first obliquely downward into said tank and thereafter obliquely upward whereby said material will be exposed to the action of a minimum amount of liquid in a maximum amount of distance.

13. An apparatus for treating material comprising a plurality of superposed, apertured, endless conveyers having adjacent parallel leads traveling in the same direction adapted to confine a thin layer of the material between them, a V-shaped tank of liquid, and means including rollers located in different horizontal planes and engaging opposite sides of said conveyers for guiding said parallel leads first obliquely downward into said tank and thereafter obliquely upward, whereby said material will be exposed to a minimum amount of liquid in a maximum amount of distance and the material squeezed between said conveyers during the passage of said leads around said rollers.

14. An apparatus for treating material comprising a plurality of superposed, apertured, endless conveyers having adjacent parallel leads traveling in the same direction adapted to confine a thin layer of the material between them, a tank of liquid, means for guiding said parallel leads first obliquely downward into said tank and thence obliquely upward, and means for vibrating said obliquely inclined portions of the conveyer transversely of their width during their passage through the tank.

15. An apparatus for treating material comprising a plurality of superposed, apertured, endless conveyers having adjacent parallel leads traveling in the same direction adapted to confine a thin layer of the material between them, a tank of liquid, means for guiding said parallel leads first obliquely downward into said tank and thence obliquely upward, and means for vibrating said obliquely inclined portions of the conveyer transversely of their width during their passage through the tank, including guides having rollers embracing said downward and upward leads, and means for reciprocating said guides.

16. An apparatus for treating material comprising a plurality of superposed, apertured, endless conveyers having adjacent parallel leads traveling in the same direction adapted to confine a thin layer of the material between them, a tank of liquid, and means including rollers located in different horizontal planes and engaging opposite sides of said conveyers for guiding said parallel leads first obliquely downward into

said tank and thereafter obliquely upward, whereby the material will be squeezed between said conveyers during the passage of said leads around said rollers, and means for vibrating said obliquely inclined portions of the conveyers transversely of their width including guides embracing said downward and upward extending leads, integral arms supporting said guides and cams for reciprocating said arms.

17. An apparatus for treating material comprising a series of tanks, a plurality of superposed, apertured, endless conveyers having parallel adjacent leads simultaneously moving in the same direction adapted to confine the material between them in a thin layer, and passing through said tanks, and means for expelling the liquid from said material as it passes from one tank to the next whereby said material may be treated successively by different agents.

18. An apparatus for treating material comprising a series of tanks, a plurality of superposed, apertured, endless conveyers having parallel adjacent leads simultaneously moving in the same direction adapted to confine the material between them in a thin layer, and passing through said tanks, means for expelling the liquid from said material as it passes from one tank to the next including squeezing rolls engaging opposite sides of said conveyers after their emergence from the liquid in the respective tanks, and means for returning the liquid to the tanks from which it was carried by the material whereby said material may be treated successively by different agents.

19. An apparatus for treating material comprising a series of tanks, a plurality of superposed, apertured, endless conveyers having parallel adjacent leads simultaneously moving in the same direction adapted to confine the material between them in a thin layer, and passing through said tanks, means for expelling the liquid from said material as it passes from one tank to the next whereby said material may be treated successively by different agents, and means for drying the material while still confined between said endless conveyers including a series of heating drums about which said material-engaging leads of said conveyers are carried.

20. An apparatus for treating material comprising a series of tanks, a plurality of superposed, apertured, endless conveyers having parallel adjacent leads simultaneously moving in the same direction, adapted to confine the material between them in a thin layer, and passing through said tanks, means for expelling the liquid from said material as it passes from one tank to the next whereby said material may be treated successively by different agents, and means for drying the material while still confined

between said endless conveyers including a series of drums about which the material-engaging leads of said conveyers are carried, said drums being located alternately 5 on opposite sides of said conveyers whereby said drums will be rotated in opposite directions by the movement of said conveyers.

21. An apparatus for treating material comprising a series of tanks, a plurality 10 of superposed, apertured, endless conveyers having parallel adjacent leads simultaneously moving in the same direction, adapted to confine the material between them in a thin layer, and passing through 15 said tanks, means for expelling the liquid from said material as it passes from one tank to the next whereby said material may be treated successively by different agents, means for drying the material while still confined between said endless conveyers including a series of drums about which the material-engaging leads of said conveyers are carried, said drums being located alternately 20 on opposite sides of said conveyers whereby 25 said drums will be rotated in opposite directions by the movement of said conveyers, and means for causing said drums to act as fans to cause the circulation of air through said conveyers and the material confined 30 therebetween.

22. An apparatus for treating material comprising a series of tanks, a plurality of superposed, apertured, endless conveyers having parallel adjacent leads simultaneously moving in the same direction, adapted 35 to confine the material between them in a thin layer, and passing through said tanks, means for expelling the liquid from said material as it passes from one tank to the next whereby said material may be treated successively by different agents, means for drying the material while still confined between said endless conveyers including a series 40 of drums about which the material-engaging leads of said conveyers are carried, said drums being located alternately on opposite sides of said conveyers whereby said drums will be rotated in opposite directions by the movement of said conveyers, and 45 means for causing certain of said conveyers to act as fans to expel the heated air from within the drum while others of said drums act as suction fans to draw air through said conveyers and the material therebetween.

50 23. An apparatus for treating material comprising a series of tanks, heating means located between adjacent tanks and means for regulating said heating means whereby the liquid in said tanks may be maintained 55 at desired temperatures, and means for passing a thin confined layer of material successively through said tanks.

24. An apparatus for treating material comprising a series of tanks having V- 60 shaped bottoms, heating means located be-

tween the bottoms of adjacent tanks and means for regulating said heating means whereby the liquid in said tanks may be maintained at desired temperatures, means for passing a thin confined layer of material successively through said tanks, comprising superposed, apertured, endless conveyers having parallel leads moving simultaneously in the same direction and adapted to confine the material between them, and 70 means for guiding said material-engaging leads of said conveyers through successive tanks.

25. An apparatus for treating material comprising a plurality of superposed series 80 of tanks adapted to contain liquid, means for passing the material in a thin layer successively through the tanks of one series and then through the tanks of the other series, and means operable to discharge the contents of any of the tanks of an upper series 85 into any of the tanks of a lower series.

26. An apparatus for scouring wool and other fibrous material comprising a series of tanks, a plurality of apertured endless conveyers having parallel adjacent leads simultaneously moving in the same direction, passing successively through said tanks and adapted to confine the fleece between them in a flat condition, said tanks being provided 90 with liquid solutions adapted successively to wash, scour and rinse said wool, and means for maintaining the liquid in said tanks at a desired temperature.

27. An apparatus for treating wool and other materials comprising a plurality of conveyers adapted to confine a thin layer of material between them, and means for treating the material while thus confined successively to dry cleaning, scouring and 100 steaming operations.

28. An apparatus for treating wool and other materials comprising a plurality of conveyers adapted to confine a thin layer of material between them, means for moving 110 said conveyers continuously in the same direction, and means for treating the material while thus confined successively to cleaning, scouring, rinsing and steaming operations.

29. An apparatus for treating wool comprising a plurality of conveyers adapted to confine a thin layer of wool between them and to maintain a tension upon the fibers of the wool, means for moving said conveyers continuously in the same direction and means 120 for treating the wool while thus confined successively to cleaning, scouring, rinsing and mercerizing operations.

30. An apparatus for treating wool comprising a plurality of conveyers adapted to 125 confine a thin layer of wool between them and to maintain a tension upon the fibers of the wool, means for moving said conveyers continuously in the same direction and means for treating the wool while it is con- 130

fined successively to cleaning, scouring, mer-
cerizing, rinsing and drying operations.

31. An apparatus for treating wool comprising a plurality of conveyers adapted to 5 confine a thin layer of wool between them, means for moving said conveyers continuously in the same direction and means for treating the wool while thus confined successively to cleaning, scouring, rinsing, 10 bleaching and drying operations.

32. An apparatus for treating material comprising a plurality of superposed, aper-
tured, endless reticulated conveyers having 15 adjacent leads moving simultaneously in the same direction, adapted to clamp the mate-
rial between them, and means for subjecting the material to the action of steam while thus retained between said conveyers.

33. In an apparatus for treating material 20 comprising a plurality of superposed, aper-
tured, endless conveyers having adjacent leads adapted to confine the material be-
tween them, and moving simultaneously in the same direction, means for expelling dirt 25 and other debris from the material, com-
prising a series of beaters overlying the up-
per material-confining lead, and means for actuating said beaters.

34. In an apparatus for treating material 30 comprising a plurality of superposed, aper-
tured, endless conveyers having adjacent leads adapted to confine the material be-
tween them and moving simultaneously in the same direction, means for expelling dirt 35 and other debris from the material, comprising a series of beaters consisting of spring plates overlying the upper material-confining lead, and means for flexing and releasing said spring plates.

40 35. In an apparatus for treating material comprising a plurality of superposed, aper-
tured, endless conveyers having adjacent leads adapted to confine the material be-
tween them, and moving simultaneously in 45 the same direction, means for expelling dirt and other debris from the material, comprising

ing a series of beaters consisting of spring plates overlying the upper material-confin-
ing lead, means for flexing and releasing said 50 spring plates, and flexible, stationary blow-
receiving means located intermediate of said spring plates and the material-engaging
means of said conveyer whereby the blow of
said beaters will be struck upon the sta-
tionary, flexible member and will be trans- 55 mitted through the same and through the
upper lead of said conveyer to the material.

36. In an apparatus for treating material comprising a plurality of superposed, aper-
tured, endless conveyers having adjacent 60 leads adapted to confine the material be-
tween them, and moving simultaneously in the same direction, means for expelling dirt and other debris from the material, comprising 65 a series of beaters consisting of spring plates overlying the upper material-confin-
ing lead, means for flexing and releasing said spring plates, a flexible, stationary blow-receiving fabric located intermediate 70 said spring plates and the material-engaging leads of said conveyers, and means for regu-
lating the tension upon said blow-receiving fabric.

37. An apparatus for treating material comprising a plurality of superposed, aper-
tured, endless, traveling conveyers having 75 adjacent parallel leads adapted to confine a thin layer of material between them, a series
of tanks, means for guiding said material-
engaging leads of said conveyers through 80 said tanks, means for drying the material
while still engaged between said material-
engaging leads, including a series of drums
having longitudinal slots provided with in-
turned walls, and means for heating the 85 drums from within, alternating drums be-
ing rotated by said conveyers in opposite di-
rections and adapted alternately to expel or
inspire air through said slots.

In testimony whereof, I have signed my 90
name to this specification.

BENJAMIN W. PUTNAM.
